COATING APPARATUS

Joseph C. Morris, Verdun, Quebec, Canada, assignor to Western Electric Company, Incorporated, New York, N. Y., a corporation of New York

Application September 2, 1936, Serial No. 99,041

9 Claims. (Cl. 91—46)

This invention relates to coating apparatus, and more particularly to apparatus for applying powdered material to strands.

It is an object of the present invention to provide an efficient and simple device for coating material.

In accordance with one embodiment of the invention wherein stearin pitch coated electrical conductors are to have a coating of powdered mica applied thereto, the strands during their passage from the pitch applying apparatus to a reel upon which they are to be stored, are passed over a table above which a hopper having a supply of powdered mica is positioned. The bottom 10 of the hopper is open and the mica dust or powdered mica placed therein will tend to drop through the hopper and onto the table. The table is provided with mechanism for shifting it laterally of the path of the wires to prevent the 15 wires from forming tunnels in the mica on the table, and removable semi-cylindrical drawers are provided which may be inverted to dump the powdered mica into the hopper after they are inserted in a housing which surrounds the hopper 20 and reciprocable table.

A better understanding of the invention will be had by reference to the following detailed description considered in conjunction with the accompanying drawing, wherein

30 Fig. 1 is an end elevational view of an apparatus for applying powdered mica to strands coated with a tacky substance such as stearin pitch, parts being broken away to show more clearly the construction of the apparatus, and

35 Fig. 2 is a side elevational view of the apparatus shown in Fig. 1, parts being broken away to show more clearly the construction of the apparatus.

Referring now to the drawing wherein like characters designate the same parts throughout the several views. A housing indicated generally by the numeral 5 is mounted upon standards 6—6 which may be placed between a mechanism (not shown) for coating strands 7 with stearin 40 pitch, and a reel (not shown) on which the coated strands are to be wound after a coating of mica dust has been applied to them to prevent them from sticking together when they are wound upon the reel. The upper portion of the housing 5 has mounted therein a hopper 8 having 45 tapering end walls 9 and 10 and tapering side walls 11 and 12, which converge to form a rectangular opening 13 through which powdered mica may be poured from a semi-cylindrical 50 drawer 14 onto a table 15.

The table 15 is comprised of a base 16 and upwardly extending sides 17 and 18 and a top portion 19. Secured to the underside of the table are a plurality of guides 25—25 which ride upon a pair of rails 26—26 secured to and extending 5 transversely of the housing 5. The left end (Fig. 1) of the table has a rod 27 secured thereto whereby the table may be moved back and forth along the rails 26.

The mechanism for reciprocating the table includes a pivoted lever 28 pivotally mounted upon a bracket 29 secured to a vertically extending member 30. The upper portion of the lever 28 is slotted, as shown at 31, to receive a pin 32 fixed to the rod 27. At its lower end the lever 28 is pinned at 33 to a reciprocable lever 35, the right end (Fig. 1) of which is bifurcated to surround a block 36 and pinned to the block at 37—37. The block 36 is mounted upon a rotatable shaft 38 having a thread 40 formed therein which cooperates with a pin (not shown) mounted in the block to form a conventional reversing screw mechanism. Power is supplied to the shaft 38 through a pulley 41 driven by a belt 42 connected to any suitable source of power (not shown).

The upper portion of the housing is provided with a pair of doors 50 and 51 whereby the strands 7 may be threaded through the apparatus. These doors are hinged to the housing at 52 and 53, respectively, and tend to prevent an excess of powdered material from escaping from the housing. At its upper portion the housing is semi-cylindrical in shape, as shown at 54, for receiving the semi-cylindrical drawer 14 and holding the drawer in either its upright or inverted position. A latching means in the form of a pair of brackets 55 is secured to the housing at a point just above the center of the semi-cylindrical portion of the housing. One end of each of the drawers is substantially cylindrical in shape having one portion 56 semi-cylindrical and of a predetermined diameter, and another portion 57 of a slightly smaller diameter so that the drawer, when in its upright position, may be pushed into the housing with the portion 56 at the bottom and may then be inverted whereby the portion 56 will pass into latching relation with the brackets 55 to hold the drawer tightly in place and make a substantially dust tight engagement with the housing.

The lower portion of the housing is in the form of a bin indicated generally by the numeral 60, having vertically disposed side walls 61 and 62, and inclined end walls 63 and 64. The lower

ends of the inclined walls 63 and 64 are joined together and bent to form a semi-cylindrical receptacle 65 for receiving another drawer 14 identical in configuration with the drawer described hereinbefore. Adjacent the end wall 64 there is pivoted a lever 66 having secured thereto a latch member 67 and a closure member 68. When it is desired to remove the drawer 14 from the bottom of the housing, the lever 66 may be moved in an anti-clockwise direction, thereby to move the closure member 68 to the position shown in the dot and dash lines and to simultaneously move the latch member 67 out of latching relation with the drawer. Handles 70 are secured to the drawers to facilitate the handling thereof.

In the operation of the apparatus, the strands 7 are strung from the pitch coating mechanism (not shown) through the mica applying device to the reels (not shown), and after the drawer 14 is inserted in the lower portion of the housing and the lever 66 moved to its full line position to latch the drawer in the lower portion of the housing, a drawer 14 having a supply of powdered mica 75 therein may be inserted in the upper portion of the housing and inverted to dump the powdered mica out of the drawer into the hopper 8 whence it will fall onto the table 15. After the machine is thus put in readiness, the reels may be started to wind the wire, and the source of power (not shown) applied to operate the belt 42, whereupon the table 15 will be reciprocated transversely to the direction of movement of the strands 7, thereby preventing the formation of tunnels in the supply of mica dust on the table 15 due to the constantly changing position of the table. As the operation of the mechanism proceeds, a certain amount of mica dust will be drawn off of the table 15 and will fall into the lower portion of the housing where it will be caught in the drawer 14 placed therein. After a predetermined interval the lever 66 may be moved to the dot and dash line position (Fig. 2), and the drawer 14 removed and transferred to the upper portion of the housing, the drawer 14 which had been in the upper portion of the housing being at the same time transferred to the lower portion and the operation may proceed, transference of the drawers taking place as soon as the supply of powdered mica in the hopper gets low.

Although a specific embodiment of the invention has been described herein, it will be understood that many modifications might be made without departing from the scope of the invention, which is to be limited only by the appended claims.

What is claimed is:

1. In an apparatus for applying powdered material to moving articles, a hopper for directing a supply of powdered material into engagement with the moving articles, a table positioned below said hopper for holding a supply of said powdered material, and means for moving said table in a direction transverse to the direction of movement of said articles.
2. In an apparatus for applying powdered material to moving articles, a stationary hopper for directing a supply of powdered material into engagement with the moving articles, a table positioned below said hopper for holding a supply of said powdered material, and means for moving said table in a direction transverse to the direction of movement of said articles.
3. In an apparatus for applying powdered material to moving articles, a stationary hopper for

directing a supply of powdered material into engagement with the moving articles, a table positioned below said hopper for holding a supply of said powdered material, and means including a reversing screw mechanism, and a pivoted lever for moving said table transversely to the direction of movement of the wires. 5

4. In an apparatus for applying powdered material to moving articles, a hopper for directing a supply of powdered material into engagement with the moving articles, a table positioned below said hopper for holding a supply of said powdered material, and means for moving said table relative to the hopper in a direction transverse to the direction of movement of said articles. 15

5. In an apparatus for applying powdered material to moving articles, a housing through which articles may be moved, a hopper positioned in the upper portion of the housing and adapted to direct powdered material to the articles, a 20 pair of rails positioned in said housing, a table movable on said rails, means for moving said table across said housing on said rails, a bin for receiving material dropped from said table, and a pair of drawers interchangeably positioned in the upper portion of the housing and in the bottom of said bin.

6. In an apparatus for applying powdered material to strands, a housing through which the strands may be moved including an upper semi-cylindrical portion, and a bin having a pair of angularly disposed walls terminating in a semi-cylindrical portion, a hopper fixed in said housing and disposed directly beneath the upper semi-cylindrical portion, a table movable beneath said 35 hopper in a direction transverse to the direction in which the articles are movable, and a pair of drawers alternately positionable in either of the semi-cylindrical portions.

7. In an apparatus for applying a coating of 40 powdered material to moving strands, a housing through which the strands may be moved, a hopper positioned in said housing for receiving a supply of said material, a table reciprocable transversely of the direction of movement of the 45 strands and beneath the hopper, and a pair of drawers semi-cylindrical in form and identical in configuration and fitting in the upper and lower portions of said housing, either of said 50 drawers being rotatable in said housing after insertion therein for dumping powdered material into the hopper.

8. In an apparatus for applying a coating of powdered material to moving strands, a housing through which the strands may be moved, a 55 hopper positioned in said housing for receiving a supply of said material, a table reciprocable transversely of the direction of movement of the strands and beneath the hopper, and a pair of 60 drawers semi-cylindrical in form and identical in configuration and fitting in the upper and lower portions of said housing, either of said 65 drawers being rotatable in said housing after insertion therein for dumping powdered material into the hopper, and latching means for holding one of said drawers in the upper portion of said housing when the drawer is in a predetermined rotatable position.

9. In an apparatus for applying a coating of 70 powdered material to moving strands, a housing through which the strands may be moved, a hopper positioned in said housing for receiving a supply of said material, a table reciprocable transversely of the direction of movement of the strands and beneath the hopper, and a pair of 75

drawers semi-cylindrical in form and identical in configuration and fitting in the upper and lower portions of said housing, either of said drawers being rotatable in said housing after insertion therein for dumping powdered material into the hopper, latching means for holding one of said

drawers in the lower portion of said housing, and means operable by said latching means for preventing powdered material from falling into said lower portion of the housing when said latch is open.

JOSEPH C. MORRIS.
